UNITED STATES PATENT OFFICE.

GUSTAV KNOCHENHAUER, OF SCHAALA, NEAR RUDOLSTADT, AND CARL BEUTHE, OF RUDOLSTADT, GERMANY.

TOBACCO-PIPE.

1,001,414.

Specification of Letters Patent. Patented Aug. 22, 1911.

Application filed July 7, 1910. Serial No. 570,852.

To all whom it may concern:

Be it known that we, GUSTAV KNOCHENHAUER, market-gardener, and CARL BEUTHE, master turner, subjects of the German Emperor, residing at Schaala, near Rudolstadt, and Rudolstadt, Thuringia, Germany, have invented certain new and useful improvements in and Relating to Tobacco-Pipes, of which the following is a specification.

Our present invention relates to improvements in and relating to tobacco pipes and has for its object to provide an improved device for intercepting saliva and dust and which device at the same time forms a connection between the pipe bowl and the mouthpiece. As such a connecting tube it voids the necessity for the usual screw threads or screwed connection between the mouthpiece and pipe, and permits, when used in meerschaum pipes for example, a wide bore to be given to the upper part, at the same time avoiding the use of the usual screwed nipple made of bone, which connects the mouthpiece with the pipe. It is well known that this screwed nipple or connecting piece in the case of meerschaum pipes can only be made with a very small bore as the meerschaum which holds this screwed connecting piece has very little strength. The small bore of the screwed piece, however, obstructs the draft in such meerschaum tobacco pipes. As however the present connecting or intermediate piece allows the meerschaum tube, as well as the mouth-piece to be made with large bores, an easy and agreeable smoke is obtained and the duration of the life of the parts of the pipe is considerably increased.

The connecting piece according to the present invention is so arranged that a disk having a central hole is put into the tube portion, which disk at the end is provided with a peripheral flange turned toward the mouthpiece of the pipe and has in the center a tubular extension which, however, does not reach up to the end of the mouthpiece. At the back of the disk toward the bowl a dust filter is provided in the shape of a wadding plug which is kept in position by means of a wire tissue and can be easily removed. The connecting piece is pushed over the mouthpiece and a short stem on the bowl, and in this way holds both these parts well together; without it

being necessary to use any of the usual connecting means such as screw threads. By using the connecting piece the manufacture of such kinds of pipes is considerably cheapened. Owing to the fact that the moisture in the pipe is for the most part due to saliva which runs along the bore of the pipe stem through the mouth piece, and that this collection of saliva is retained in the connecting piece by the tubular extension which projects toward the mouthpiece, and therefore cannot reach to the pipe bowl, a clean smoke and good and regular combustion of the tobacco which does not get moist is obtained. By removing the mouthpiece the collected moisture may easily be removed from the connecting piece. The filter retains the tobacco dust which is drawn from the bowl by the suction in smoking.

Figure 1 is a side view of the pipe, partly in section, illustrating one form of our invention. Fig. 2 is a cross sectional view on line A—B of Fig. 1. Fig. 3, is a cross sectional view on line C—D of Fig. 1.

The disk *b* has at its back the filter comprising a cartridge *c* which is held in position by means of a suitably large-meshed tissue *e*. The end *a¹* of the connecting piece is connected to the mouthpiece at the end *e¹*. The stem of the pipe *f* is inserted in the other end *a²* of the connecting piece. The sockets *a¹* and *a²* may be slightly tapered so as to make a sufficiently tight joint with the mouthpiece *c*, and the tube *f* of the pipe piece *g*.

When the pipe is in use the saliva which flows from the mouthpiece collects in the annular chamber between tube *d* and the top part of the connecting piece *a*, and can easily be poured out of this chamber after pulling out or twisting off the mouthpiece. When drawing at the mouthpiece, the tobacco smoke passes through the filter or dust collector *e*, and enters the mouthpiece freed from dust through the tube *d*.

A similar connecting piece may also be used for cigar holders and long pipes. As already mentioned it permits of an easy connection between the pipe bowl tube and the mouthpiece, which is permanently insured and renders the provision of special screwed pieces between the bowl tube piece and the mouthpiece unnecessary. Nor does it cause the pipe to draw hard. This connecting piece is also very suitable for clay

pipes. For this purpose the stem of the pipe is interrupted and the connecting piece interposed.

What we claim is:—

- 5 1. The combination with a pipe bowl and a stem, of a relatively elongated sleeve connecting the stem and bowl with the ends of the bowl and stem relatively widely separated, a cartridge of fabric dividing the sleeve into two compartments and located at a relatively considerable distance from the facing ends of the bowl and stem, and a disk-like member engaging the cartridge on that side thereof next to the stem and having a central opening disposed therein, said member having an inner tubular projection extending from said opening toward but not into contact with the stem, and an outer tubular member surrounding said inner projection and engaging and disposed wholly within said sleeve.
- 10 15 2. The combination with a pipe bowl with a stem, of a relatively elongated sleeve connecting the stem and bowl with the ends

of the bowl and stem relatively widely separated, a cartridge of fabric dividing the sleeve into two compartments and located at a relatively considerable distance from the facing ends of the bowl and stem, and a disk-like member engaging the cartridge on that side thereof next to the stem and having a central opening disposed therein, said member having an inner tubular projection extending from said opening toward but not into contact with the stem, and an outer tubular member surrounding said inner projection and engaging and disposed wholly within said sleeve.

In testimony whereof we have hereunto set our hands in presence of two subscribing witnesses.

GUSTAV KNOCHENHAUER.
CARL BEUTHE.
